UNITED STATES PATENT OFFICE

JOHN C. WENDLING, OF CLEVELAND, OHIO, ASSIGNOR OF ONE-HALF TO FREDERICK H. SCHLEGELMILCH, OF ASHTABULA, OHIO.

ENGINE-VALVE.

1,166,163.

Specification of Letters Patent. Patented Dec. 28, 1915.

Application filed February 17, 1915. Serial No. 8,788.

To all whom it may concern:

Be it known that I, JOHN C. WENDLING, a citizen of the United States, residing at Cleveland, in the county of Cuyahoga and State of Ohio, have invented certain new and useful Improvements in Engine-Valves, of which the following is a specification.

This invention relates to improvements in valve mechanism for four cycle internal combustion engines, wherein a box valve of simple construction co-acts with the piston in timed relation to the inlet and exhaust ports, whereby the admission of the live gas to the cylinder, and the exhaust of the 15 burned gas therefrom are controlled by the same valve.

The objects of the invention are provision of a simple and durable valve construction that is highly efficient in operation, that minimizes the expense of construction and 20 repairs, that is readily adjustable to take up the wear on the parts, to provide for thorough and effective lubrication and to eliminate in a great measure the liability 25 of expansion or warping of the operative parts through excessive heat.

The present invention provides for a box valve adapted to slide in a valve chamber transversely to adjacent inlet and exhaust 30 ports, the said valve being actuated by certain operative means co-acting in timed relation with the piston for opening and closing the ports at the proper time through the cycles of operation of the engine.

The invention is applicable to either single cylinder or multi-cylinder engines, and to avoid encumbering the specification the 35 description will be confined to a single cylinder as the same would apply to all the 40 cylinders.

In the drawings forming a part of this specification, Figure 1 is a vertical section through the center of the cylinder and the valve mechanism, showing the relative position of the valve, piston, and other operative 45 parts at the time of the explosion. Figs. 2, 3, and 4 illustrate the relative position of the valve to the intake and exhaust ports in the exhaust, intake, and compression 50 strokes, respectively. Fig. 5 is a view of the

valve member detached and in direction of arrow in Fig. 1. Fig. 6 is an enlarged transverse section of the valve member on line 6—6 Fig. 5 and Fig. 7 is a similar section on line 7—7 Fig. 5. Fig. 8 is a fragmentary view of an adjustable wearing plate.

Similar characters of reference are used to designate similar parts in the drawings and description.

I am aware that a patent has been granted for a combustion engine embodying valve mechanism wherein two flat plates provided with ports, have a reciprocating movement on each other and transversely to the intake and exhaust ports for opening and closing said ports in timed relation to the cycles of operation of the engine, and in an application filed by me November 27, 1914, Serial No. 874,137, and now pending, I have described substantially the same operation, but as far as I know there has not been used a reciprocating box-valve for this purpose, and while the broad principles in regard to the admission and exhaust of the explosive material is the same, the particular construction of the valve is such as to render the engine more efficient.

Referring to the drawings 1 represents a cylinder of an internal combustion engine 80 of the four cycle type equipped with the improved valve mechanism, 2 the piston, 3 the connecting rod, and 4 the crank-shaft. The exhaust port 1^a and the intake port 1^b are located adjacent and in alignment one above 85 the other on the same side of the cylinder. The ports just referred to open into a valve chamber 5. Ports 5^a and 5^b are arranged in the same horizontal plane opposite the ports 1^a and 1^b and communicate with the exhaust 90 6 and the intake 7, respectively. The cylinder and valve chamber are suitably water jacketed for cooling purposes, water circulating means being provided but not shown.

The valve for controlling the admission 95 and exhaust in timed relation to the cycles of operation of the engine, is of box construction substantially as follows: The member 8 is rectangular in shape and is provided with lateral ribs 8^a, 8^b. A flat 100

cover plate 9 of the same shape and surface area as the member 8 is connected with the said member 8, preferably by means of dowel pins 10, although screws with 5 counter-sunk heads or other means may be used, the dowel pins or screws entering the ribs 8^a, 8^d. The combination of the member 8 and the cover plate 9 forms a box casing in which a valve member 11 is adapted to 10 slide having a face bearing on the members 8 and 9, and side or edge bearings on the ribs 8^a, 8^d. The member 8 is provided with two slots 8^a and 8^b, and the cover plate 9 has slots 9^a and 9^b of the same area and in 15 the same plane as the slots 8^a and 8^b. The valve member 11 is provided with slots 11^a and 11^b of substantially the same area as the slots in the member 8 and in the cover 9, and so arranged that in the sliding movement of 20 the member 14 in the box, when the slot 11^a registers with the slots 8^a and 9^a, the slot 11^b is out of registration with the slots 8^b and 9^b, and vice versa, or in other words when open communication is established 25 through one series of slots it is cut off through the other series. The member 11 is actuated by means of a connecting rod 12 pivotally attached to a depending tongue 11^c and operated in the manner hereinafter 30 explained. While the member 11 has a reciprocating movement between the members 8 and 9, the said members 8 and 9 have a reciprocating movement in the valve chamber separately but relatively to that of the member 11 and in relation to the intake and 35 exhaust ports, the box being actuated by means of a connecting rod 13 pivotally attached to the tongue 8^c depending from the member 8 and operated in the manner presently set forth.

The valve chamber 5 is provided with a wearing plate 14 having openings 14^a and 14^b registering with the ports 1^a and 1^b. An adjustable wearing plate 15 is also provided 45 on the opposite side of the valve chamber and having openings 15^a and 15^b in line with the ports 5^a and 5^b but slightly larger than said ports, to admit of adjustment of said plate without covering the ports.

50 The member 11 and the box made up of the members 8 and 9 are operated in timed relation to the piston action by the co-operating mechanism as follows: An operative connection—in this case—of a two to one 55 ratio is provided between the main crank-shaft 4 and a secondary crank-shaft 16. In the engine illustrated in Fig. 1 this connection is through the medium of gears 4^a and 16^a, this gear construction however is not 60 arbitrary, the same result being obtainable by other well known means. The member 11 and the box of the valve are eccentrically connected with the crank-shaft 16 by connecting rods 12 and 13. The distance of

throw of the eccentric rod 12 is the same as 65 that of the rod 13 and is governed by the predetermined relative positions of the ports 1^c, 5^a and the slots 8^a, 8^b, 9^a, 9^b, 11^a and 11^b, it is however, essential, if a two to one ratio 70 connection between the crank-shafts is used, that the rod 13 is 60° in advance of the rod 12 to obtain the correct timing of the co-operating mechanism.

Referring now to Figs. 1, 2, 3 and 4, the several important stages of the operation 75 will be explained. This will be found to be substantially the same as that described in my former application above referred to. In Fig. 1 the piston is at its extreme upward position, ready for the explosion, and 80 the ports 1^a and 1^b are closed. The explosion of course forces the piston downward, in the next one-half revolution of the main crank-shaft, or the full stroke of the piston, the crank-shaft 16 makes a one-quarter revolution, owing to the two-to-one ratio of the 85 gears 4^a and 16^a, this brings the parts to the position shown in Fig. 2. During this one-half cycle of the main crank-shaft the box of the valve travels faster than the valve 90 plate 11, carrying the slots in the box and in plate 11 to the relative position as shown, thereby opening the exhaust ports. The next half cycle closes the exhaust and opens 95 the intake ports, as shown in Fig. 3, admitting the gas to the cylinder. The piston then assumes the position shown in Fig. 4, with the exhaust and intake ports closed, and during the next operation of the piston 100 the compression takes place, and the several co-operating parts are brought to the first or explosion position shown in Fig. 1.

Thorough lubrication of the valve is provided through a pipe 17 connected with the upper part of the valve chamber 5 and with 105 a pump, not shown, but which may be located in any suitable position and operatively connected with the engine.

The distance between the walls 5^c and 5^d of the valve chamber 5 is greater at the top 110 than at the bottom of said chamber, the wall 5^d being at a slight angle to the wall 5^c, and the two faces of the bearing plate 15 are at 115 the same angle to each other as the walls of the chamber. This provides a wear take-up, or an adjustment of the valve chamber relative to the valve box. The adjustment of the plate 15 is regulated by the screws 18 threaded in the cap 19 and swiveled in the plate 15, the slots 15^a and 15^b being of 120 greater area than the ports 5^a and 5^b admit of the raising or lowering of said plate for adjustment, without decreasing the area of said ports.

The numerous advantages of this improved box valve construction will readily be seen. It admits of a direct line longitudinal, reciprocating movement of the member

11 in the box member of the valve. It provides a double adjustment of the parts, namely, the adjustment between the box member and the plate 11, and the adjustment between the box member and the valve chamber. It also reduces to a minimum the liability of expansion of the parts by furnishing perfect means for lubrication to all bearing surfaces. It is easy to assemble, 10 and readily accessible for repairs, and provides a most efficient valve.

It will be understood that the invention lies wholly in the valve construction and in its combination with the engine.

15 What I claim and desire to have secured to me by Letters Patent is.

1. In a valve for four cycle internal combustion engines, the combination of a valve chamber provided with adjacent intake and 20 exhaust ports; a box valve member slidable in said chamber and provided with two slots in each of the adjacent sides, a valve plate slidable within the box member, said plate being provided with two slots; and means 25 for actuating the plate and box member reciprocably, separately but relatively to bring the slots in said plate and in the box member into and out of registration with each other and with the intake and exhaust ports.

30 2. In a four cycle internal combustion engine provided with adjacent inlet and exhaust ports opening into a rectangular valve chamber, ports from said valve chamber opening into the cylinder in the same 35 plane with the first mentioned ports, a box valve member slidable in said chamber transversely to the ports, said box being provided with two slots in each of its adjacent sides, the slots in one side being in the same plane 40 with corresponding slots in the adjacent side; a valve plate slidable between the two adjacent sides of the box member, said plate being provided with two slots of the same area as the slots in the box member; and means 45 for actuating the plate and box member reciprocably, separately but relatively to bring the slots in the valve plate and in the box member into and out of registration with each other and with the intake and exhaust 50 ports.

55 3. In a four cycle internal combustion engine a cylinder with adjacent inlet and exhaust ports and a rectangular chamber into which the ports open, continuations of said ports on the opposite side of the chamber, a box valve member having a reciprocatory movement in the chamber transversely to the ports and having two slots in each of its adjacent sides, a valve plate slidable within 60 the box bearing on the sides thereof, said plate being provided with two slots spaced differently from those in the box member but of the same area, and means for actuating the plate and box member reciprocably,

separately but relatively to bring the slots 65 in the valve plate and in the box member into and out of registration with each other and with the intake and exhaust ports in timed relation to the cycles of operation of the engine.

70 4. In a valve for four cycle internal combustion engine, the combination of a rectangular valve chamber provided with intake and exhaust ports; a valve member consisting of a rectangular plate provided 75 with lateral longitudinal ribs, a rectangular cover plate attached to said ribs, thereby forming a box open at both ends and having two slots in each of the plates, a rectangular plate slidable within the box and provided 80 with slots of the same area as the slots in the box member but differently spaced; means for actuating the plate reciprocably in the box; and means for actuating the box reciprocably in the valve chamber in 85 timed relation for opening and closing the intake and exhaust ports.

5. In a valve for four cycle internal combustion engines, the combination of a rectangular valve chamber provided with intake and exhaust ports; an adjustable wearing plate in said valve chamber; a valve member consisting of a rectangular plate provided with lateral longitudinal ribs, a rectangular cover plate attached to said ribs 90 thereby forming a box provided with two slots in each of the plates, a rectangular plate slidable in the box and provided with slots of the same area as the slots in the box member but differently spaced in longitudinal relation; means for actuating the plate reciprocably in the box; and means for actuating the box reciprocably in the valve chamber in timed relation for opening and closing the intake and exhaust ports.

95 6. A valve for four cycle internal combustion engines consisting of a rectangular box having two slots in each of two opposing members thereof, a rectangular valve plate adapted to slide longitudinally in said box 100 and bearing on said opposing members and having slots therein of the same area as the slots in the box but differently spaced in longitudinal relation.

105 7. In a four cycle internal combustion engine the cylinder of which is provided with adjacent intake and exhaust ports, the combination of a rectangular valve chamber having ports in the same plane as the cylinder ports; a rectangular box valve member 110 slidable in said valve chamber transversely to the ports and provided with intake and exhaust ports of the same area as the chamber ports; an adjustable wearing plate interposed between the box member and the 115 wall of the valve chamber; a valve plate provided with slots of the same area as the slots in the box member but differently

spaced, said valve plate reciprocably movable in the box member; means for actuating said box member; and means for actuating the valve plate in the box to cause the 5 slots in the plate and the slots in the box to register with each other and with the in-

take and exhaust ports in timed relation to the movements of the engine piston.
